(57) **CLAIM**

The ornamental design for a jewelry pendant, as shown and described.

DESCRIPTION

FIG. 1 is a perspective view of a first embodiment of a jewelry pendant showing our new design;

FIG. 2 is a front elevational view of FIG. 1;

FIG. 3 is a left end view of FIG. 1, the right end view being a mirror image thereof;

FIG. 4 is a top plan view of FIG. 1;

FIG. 5 is a bottom plan view of FIG. 1; and,

FIG. 6 is a perspective view of FIG. 1 in a disengaged state. The broken lines shown in the drawings illustrate environmental matter, and form no part of the claimed design.
